RADIO TRANSMITTING ARRANGEMENT

Erich Stutius, Berlin, Germany, assignor to C. Lorenz Aktiengesellschaft, Berlin-Tempelhof, Lorenzweg, Germany, a company

Application March 3, 1938, Serial No. 193,641
In Germany April 12, 1937

4 Claims. (Cl. 250—11)

The present invention is an improvement upon radio beacons of the kind disclosed in United States Patent 2,028,510, issued January 21, 1936. The arrangements there specified by way of example comprise a continuously fed transmitting dipole and two reflecting dipoles arranged to be periodically and alternately interrupted by relay contacts, each reflecting dipole thus being subjected to a keying operation in accordance with the operation of the relays controlling these contacts and therefore designated as keying relays. One of such relays is a working relay, its contact being a make contact, while the other is a resting relay, its contact being a break contact. In this way it is possible with the aid of simple means to provide for a keying operation by which signals of one kind and signals of a second kind are produced in such succession that the signals of each kind are originated in the intervals between those of the other kind, whereby the two signals, being complementary to each other, shall constitute a combination signal of equal field intensity and therefore designated as continuous dash line. This signal enables aircraft pilots to ascertain whether they are on or off the course to be followed, since when leaving this course either one or the other kind of complementary signal will predominate.

It is however difficult so to adjust the keying relays of these arrangements that any two of the complementary signals shall be precluded from overlapping each other. This is mainly due to the fact that the material from which the contact springs of the relays are made is not of the same quality or properties throughout. Therefore United States Patent 2,072,268, issued March 2, 1937, proposes that the circular radiation characteristic or pattern of the transmitting dipole, that is, the radiation pattern produced when both reflecting antennae are ineffective, be calculated to extend through the points of intersection of the two directional radiation patterns, that is, the patterns which are alternately produced by keying the reflecting antennae, jumps in the field strength thus being prevented. In this way it is rendered possible so to adjust the keying relays that the reflecting antennae shall not become effective simultaneously, tolerances, that is, short periods being provided during which both reflectors are ineffective.

The invention provides for regulating in a simple manner the pull-up and release times of the keying relays, thus enabling the said tolerances to be adjusted. A subsidiary feature of the invention resides in the provision of a checking device by which the adjustment to which the relays and hence the said tolerances are subjected can be ascertained.

In accordance with the invention the pull-up and release times of the keying relays are regu-

lated with the aid of resistances and an auxiliary relay which at a certain instant of time acts to connect these resistances in parallel with the windings of the keying relays. This auxiliary relay is slow-acting, its time lag however being so calculated that the contacts of this relay shall not affect the keying operation.

The invention will be understood from the following description, reference being had to the accompanying drawing showing one embodiment of the invention.

The antenna arrangement comprises a dipole E, which in the operation of the arrangement is continuously fed from a high frequency generator S, and two reflecting dipoles I, II intended alternately to be rendered effective and ineffective so that by means of each of these reflectors signals are produced in the intervals in which the other reflector is ineffective. The working relay for keying reflector I is designated A while the resting relay employed for keying the reflector II is designated R. Relay A has a contact *rA*, located in dipole I, while relay R has a contact *rR* that forms part of dipole II. These relays are included in a circuit which also contains a slow-acting relay H, this being the aforesaid auxiliary relay, a variable resistance *e*, a key T, and a battery B. With the key T opened, as shown, both relays are in their state of deenergization in which contact *rA* is open while contact *rR* is closed. The pull-up times of both relays can be adjusted with the aid of variable resistances *a*, *b*, whereas the release times thereof are regulable by means of variable resistances *c*, *d*. These resistances are connected to each other and to battery B and relays A, R through certain contacts *h1* and *h2* in such manner that with *h1* and *h2* in the positions shown resistors *c* and *d* shunt the windings of relays A and R respectively, whereas with contacts *h1* and *h2* shifted resistances *a* and *b* shunt the windings of relays A and R respectively, as clearly shown in the drawing. *h1* and *h2* are two contacts of relay H which are arranged as change-over contacts. The object of adjusting in this way both the keying signals and the said tolerances is, to finish the signals abruptly and to commence them slowly, in order thereby to preclude the reflectors from becoming effective simultaneously. From this it follows that relay A must be sluggish in attracting its armature while dropping it quickly, and further, that relay R must be sluggish in dropping its armature while attracting it quickly. Therefore, resistance *a* acting to regulate the pull-up time of relay A, must be relatively low while resistance *c*, by which the release time of this relay is regulated, must be relatively high; similarly, resistance *b*, acting to regulate the pull-up time of relay R, should be high whereas resistance *d*, having to regulate the release time of relay R, should be low. Relay H al-

though slow-acting switches its contacts within the time taken for producing a signal by depressing the key T, whereby these contacts can not affect the keying operation.

5 Resistance e serves for adjusting the time lag of relay H.

This adjusting device is preferably arranged in the transmitter room. The terminals 1, 2, 3 of this device, which are located in such room, are 10 by suitable lines L1, L2, L3 connected to the terminals 1', 2', 3' of the antenna arrangement E, I, II.

The arrangement shown in the right hand portion of the drawing has for its object to check 15 the short intervals during which both contacts rA, rR are opened. The permissible variations in the length of any such short interval may be specified by maximum and minimum tolerance limits t_2 and t_1 . The checking device shown at 20 the right of the drawing may be used to check at any time whether the actual lengths of the intervals are between the specified tolerance limits, such checking being performed both with respect to the interval between the pull up of relay 25 R and that of relay A when key T is closed and also with respect to the interval between the release of relay A and that of relay R when key T is opened. The indications are given by a glow lamp which lights or fails to light dependent upon 30 whether the intervals being checked are longer or shorter than the tolerance limit with respect to which the test is made.

The contacts rA, rR are so connected to points 4, 5 of a bridge 6, 7, 8, 9 that the space 35 between the points 4, 5 is bridged over if any one of these contacts is closed. By such contact closure the parts C1, C2, G are short-circuited, the energy of bridge battery B' flowing within the bridge since either closed contact rA or closed 40 contact rR, as the case may be, is included therein. However from the instant of opening one of these contacts up to the instant of closing the other the space between points 4, 5 will not be bridged. This interval, during which in this 45 way the points 4, 5 are not interconnected by either one or the other of the contacts rA, rR is to be within the tolerance $t_2 - t_1$. To determine whether the actual length of the interval is between the upper and lower tolerance 50 limits t_2 and t_1 , the switch S3 is closed to connect bridge battery B' in circuit and the switch S2 is moved to make contact with first the contact t_2' and then the contact t_1' . If the actual 55 lengths of the intervals (during which both reflectors I and II are ineffective) is between the specified limits t_2 and t_1 the grid glow lamp G should flash at each opening or closing of the key T when the switch S2 is set to the upper contact t_1' but should fail to flash when the switch 60 S2 is set to the lower contact t_2' .

The manner in which such operation takes place is as follows: The momentary interruption of the bridge between points 6 and 7, which results from the simultaneous opening condition of 65 contacts rA and rR, causes battery B' to charge either the condenser C1 or condenser C2 over resistances R1, R2, depending whether switch S2 has been brought to rest against contact t_1' or contact t_2' . The voltage of these condensers, 70 being dependent upon the capacity and duration of the charge, is so chosen that the duration t_1 or t_2 , as the case may be, shall cause the ignition voltage of the glow lamp G to be attained, this

lamp thus being lit accordingly to indicate that the desired duration t_1 or t_2 is effective.

A voltmeter V is arranged to indicate the voltage of battery B' which is switched in by means of a switch S3.

h denotes a change-over contact of relay H. This contact may be a third contact thereof, being provided in addition to the contacts h1, h2, or may be either one or the other of these two. In each case such contact h is connected in parallel with the contacts rA, rR over a hand-operated switch S1, those openings of circuit 4-5 corresponding to the differences of time involved in the release of the relays A, R or else those circuit openings corresponding to the differences 15 in the operating times of these relays are bridged over depending whether switch S1 is brought to rest against contact t or contact u. The arrangement h, S1, t, u may thus serve for ascertaining the pull-up and release times of the keying 20 relays independently of each other.

What is claimed is:

1. Radio transmitter arrangement comprising a main antenna, a high frequency generator coupled thereto, two reflecting antennae for modifying the radiation of said main antenna, a working relay having a make contact connected in one of said reflecting antennae, a resting relay having a break contact connected in the other of said reflecting antennae, a circuit for energizing said relays, keying means for opening and closing said circuit, two auxiliary make contacts and two auxiliary break contacts, an auxiliary relay connected in said circuit to be energized and deenergized by said keying means and adapted to open said auxiliary break contacts and close said auxiliary make contacts in response to said energization and deenergization with a delay sufficiently great so that the rapidity of the actuation of such contacts exerts no influence upon the rapidity of response of said working and resting relays, adjustable resistances connected in parallel with the working and resting relays through said auxiliary relay make contacts for controlling the operating time of said working 40 and resting relays, and further resistances connected in parallel with said working and resting relays through said auxiliary relay break contacts for controlling the release time of said working and resting relays. 45

2. An arrangement according to claim 1, comprising condensers, a glow lamp under control of these condensers, and means under control of the working and resting relays for charging such condensers during the intervals in which both said 50 relay contacts are opened.

3. An arrangement according to claim 1, comprising condensers, a switch to connect either one or another of these condensers with said relays, means under control of the working and resting relays for charging said condensers during the intervals in which both said relay contacts are open, and a glow lamp under control of the charged condenser. 60

4. An arrangement according to claim 1, comprising condensers, a glow lamp under control of these condensers, means under control of the working and resting relays for charging said condensers during the intervals in which both said relay contacts are open, and a switch adapted to connect a change-over contact of the said auxiliary relay in parallel with said relay contacts. 65
